PLOW.

1,297,594.

Specification of Letters Patent. Patented Mar. 18, 1919.

Application filed August 11, 1913. Serial No. 784,113.

To all whom it may concern:

Be it known that I, CHARLES T. RAY, a citizen of the United States, residing at Louisville, in the county of Jefferson and State of Kentucky, have invented new and useful Improvements in Plows, of which the following is a specification.

This invention has relation to plows or plow bodies, hereinafter for convenience called "plows" comprising a frog, a share and a landside, and one of the most important objects is to so form and correlate these parts that they mutually brace each other and coöperate to form a plow of exceptionally rigid and well balanced construction. In other words, one of the most important objects of the invention is to provide a novel construction of the various parts of a plow and an improved manner of fitting these parts together whereby the rigidity necessary to preserve the pitch, balance and durability of the plow is insured and the parts are held firmly in place and prevented from becoming loose or shaky. Another important purpose is to so construct and correlate the parts that the strains due to plowing will not be transmitted to the bolt used to connect the share to the frog.

These objects and others which will be understood by those familiar with this invention and the art to which it relates, are well secured by the construction illustrated in the accompanying drawings, and which construction has been selected as exemplifying the best embodiment of the invention now known to me. It should be understood, however, that changes in the details may be made without departing from the spirit of the invention or the scope of the subjoined claims.

In the drawings, wherein like characters of reference, designate corresponding parts in the different views:

Figure 1 is an inverted perspective view of the plow, the parts being shown in assembled relation;

Fig. 2 illustrates in perspective, the frog landside and share in spaced relation;

Fig. 3 is a detail representation of the share, showing the same as it appears when tilted away from the observer and viewed toward the inner side; and

Fig. 4 is a detail perspective view showing the upper front corner of the frog and the adjacent parts of the share and moldboard.

Referring to the drawing in detail, the invention comprises a frog A, landside B, share C and moldboard D.

The frog A is of angle construction including the substantially straight landside 60 side 5 and a wing 6, which wing is laterally inclined and rearwardly divergent from the front end of the side 5, the correlation of the side 5 and wing 6 being such that the front end 29 of the frog is substantially pointed. 65 This front end, moreover, is rearwardly inclined upward from the lower end of the frog. At the junction of the lower front ends of the side 5 and wing 6 a nose 7 is formed. The lower portion of the outer face 70 of the landside side 5 of the frog is formed with a longitudinally extending recess or cut away portion 8 to receive the landside B, whose forward edge is thus aligned with and forms substantially a continuation of the 75 front edge of the frog thereabove. This landside B has its lower rear portion or heel flanged as usual, the forward end of the flange gradually merging into the lower edge of the forward part or toe of the landside, as shown at 10^a. The upper edge 10 of the landside B engages the shoulder 9 formed by the recess 8. The landside B is held against the landside side 5 of the frog by suitable means—as bolts 11, for example—and is prevented from rising by the shoulder 9. The lower edge of the forward portion of the frog has a projection 5^a which extends to the horizontal plane of the bottom surface of the flange of the landside B, 90 the rear portion of the frog resting upon the upper surface of the flange of the landside, as clearly shown in Fig. 1.

The share C is pointed as usual, and includes a landside side 12 which is flush with the outer surface of the landside B when the parts are assembled. It also includes a rearwardly divergent, laterally inclined wing 13 which rests upon the wing 6 of the frog and in practice is preferably connected thereto 95 by a suitable element as the bolt 14, for example. It may be here mentioned that this bolt is not essential in holding the share in position while plowing, and is employed merely to hold the share against the frog 100 and landside when the plow is moved backward against a resisting substance: the frog, landside and share being mutually formed to provide at their contiguous portions, lugs forming shoulders, or the like, presently to 110

be described, which engage each other and hold the share in position, the correlation of the parts being such, moreover, that the strains due to plowing will not be transmitted to the bolt 14.

The moldboard D is suitably secured to the wing 6 of the frog and its forward edge conforms in shape to and engages the rear edge of the share C, the latter as clearly shown being curved. A bolt 15 constitutes a suitable means for securing the holdboard D to the wing of the frog; and the rear end of the moldboard is held against lateral movement by a brace 16 which is secured to the moldboard and to the landside B.

In order to rigidly connect the parts, I have constructed the plow so that the share will be interlocked with both the frog and the landside. To this end the lower edge 20 of the wing 6 of the frog is formed with a notch or seat 17: the landside side of the nose 7 of the frog has a recess 22 with a lug 21 at the rear end thereof: the forward end 23 of the landside B, which substantially conforms in shape to the forward end of the frog, has a recess 25 in its under side, this recess registering with the portion of the recess 22 below the lug 21 and forming a lug 26 which rests against said lug 21: the share C has its wing 13 provided with a lug 18 which engages the notch or seat 17 in the wing of the frog and also has its landside side provided with a lug 20 forming a shoulder which extends into the 35 registering recesses formed in the landside side of the frog and in the landside, and engages beneath the lugs 21 and 26. The width of the lug 20 is substantially equal to the combined thickness of the lugs 22 and 26.

The share C further comprises a shin 27 one side of which consists of a wall 24 which forms a continuation or extension of and lies in the plane of the landside side 45 12 of the share and the other side of which forms a continuation or extension of the wing 13. At its upper end the shin 27 carries a rearwardly projecting shoulder 30 which engages a shoulder 31 formed by the 50 upper front corner of the frog A. The share is formed with a rearwardly facing abutment 28 which extends from the shoulder 30 to the lug 20 and lies substantially at right angles to the landside face of the 55 share. The upper part of this abutment is curved to conform to the shape of the front edge of the upper portion of the frog and its lower part conforms to the shape of the forward end 23 of the landside B; 60 said abutment, when the parts are assembled lying against said parts of the frog and landside.

It will therefore, be seen that when the parts are brought into assembled relation 65 the rear face of the wing 13 of the share

lies against the front face of the wing 6 of the frog with the shoulder formed by the lug 20 complementally engaged by the shoulders formed by the lugs 21 and 26 and with the lug 18 of the share engaged with the 70 seat 17 of the wing of the frog. The parts are further interconnected by the engagement of the shoulder 30 with the shoulder 31. In addition the rearwardly facing abutment bears against the surface complementally presented by the upper front edge of the frog A and the front edge 23 of the landside. This abutment lies substantially at right angles to the landside face of the share and constitutes a square shoulder which takes the rearward thrust of the share and aids in relieving bolt 14 of all shearing strain.

Furthermore, when the lug 20 enters the recess 22 the nose 7 of the frog enters the 85 space 19 formed between the lug 20 and the rear face of the lower portion of the wing 13.

Consequently, it will be seen that the structure is such as to secure the parts effectually in assembled relation and transmit the strain brought upon the share in plowing to the frog with practically no strain whatever upon the bolt 14, said bolt serving, as before stated, merely to hold the 95 share against movement away from the wing 6 when the device is not in use or when the plow is pulled rearwardly.

Having thus described the invention, what I believe to be new and desire to secure by Letters Patent, is:

1. A plow comprising a frog having its landside side provided with a forwardly open undercut recess, a landside engaging the landside side of the frog and provided at its front end with a forwardly open undercut recess alined with the recess in the frog, and a share having a portion which bears against the forward end of the landside and is provided with a rearward projection which is received by the recesses in both the frog and landside.

2. A plow comprising a frog having a landside side, a landside secured thereto, the front end of which alines with a forward portion of the frog to form therewith a front edge extending substantially throughout the height of the frog, a share having a rearwardly facing abutment which bears upon said edge substantially throughout its height and a rearwardly directed projection at the bottom of said abutment, said landside and frog being complementally provided with undercut recesses in which said projection is received.

3. A plow comprising a frog having a recessed portion at its forward end and a nose projecting forwardly of said recessed portion, a landside having a recessed portion at its forward end which laterally alines

with the recessed portion of the frog, and a share having a rearwardly projecting lug at its lower rear portion which is complementally engaged within the recess of the 5 landside and frog said frog having a cavity in its underside inwardly of the lug into which the nose of the frog projects.

4. A plow comprising a frog having a recess at its forward end, a landside having 10 a recess at its forward end which laterally alines with the recess of the frog and a share having a rearwardly projecting lug at its lower rear portion which is complementally engaged within the recesses of the frog and 15 landside.

5. A plow comprising a frog having a recess at its forward end and a nose projecting forwardly of said recess, a landside having a recess at its forward end which laterally 20 alines with the recess of the frog, a share having a rearwardly projecting lug at its lower rear portion and a rearwardly facing abutment, the said lug being complementally engaged within the recesses of the landside 25 and frog and the abutment engaging with the front end of the landside.

6. A plow comprising a frog recessed at its lower end in a way to provide an overhanging lug, having an abrupt shoulder at 30 its front end and a nose projecting in advance thereof and a share having a rearwardly projecting lug at its lower rear portion which engages beneath said overhanging lug said share having a rearwardly facing abutment above said rearwardly projecting lug shaped to conform to and be engaged by said abrupt shoulder.

7. A plow comprising a frog having its landside side provided with a forwardly 40 open undercut recess, a landside engaging the landside side of the frog and provided at its front end with a forwardly open undercut recess alined with the recess in the frog, the frog having a nose projecting 45 forwardly beyond said recesses, and a share having a rearwardly projecting lug at its lower rear portion which enters the recesses of the frog and landside, the share also having a cavity in its underside, inwardly of 50 said lug, to receive the nose of the frog.

8. A plow comprising a frog having a landside side, a landside secured thereto, the front end of the landside alining with that part of the frog thereabove to constitute 55 therewith a forwardly facing edge, the frog being provided with a forwardly open recess and a nose projecting forwardly beyond said recess, the landside having its forward edge provided with a recess alined with the recess in the frog, and a share extending substantially the full height of the frog and having a portion which bears against the before-mentioned forwardly facing edge, the share also having a rearward projection which enters the recesses in the frog 60 65

and landside and a cavity inward of the projection to receive the nose of the frog.

9. A plow comprising a frog having a front edge and a recess in its base, and a share having a rearwardly facing abutment 70 which bears against said edge, said share also having rearward projections at the top and bottom respectively of the abutment, the upper projection engaging over the top of the frog and the lower projection entering 75 the recess formed in the base of the frog.

10. A plow comprising a frog having a landside side, a landside secured thereto, the front end of the landside alining with that part of the frog thereabove to constitute 80 therewith a forwardly facing edge, the frog being provided with a forwardly open recess and a nose projecting forwardly beyond said recess, the landside having its forward edge provided with a recess alined 85 with the recess in the frog, and a share having a rearwardly facing abutment which bears upon the before-mentioned forwardly facing edge and also having rearward projections at the top and bottom respectively 90 of the abutment, the upper projection engaging over the top of the frog and the lower projection entering the alined recesses in the frog and landside, the share also having a cavity inward of its lower projec- 95 tion to receive the nose of the frog.

11. In a plow, the combination with a frog having a front edge and a wing, a share having a shin which extends to the top of the frog and a wing which conforms to and rests 100 upon the wing of the frog, the share also having a rearwardly facing abutment which is engaged by the forward edge of the frog and lugs at the top and bottom of said abutment, said lugs respectively engaging the 105 top and bottom of the frog, the share also having its wing formed with a lug which engages the wing of the frog.

12. In a plow, the combination with a frog having a front edge, a wing and a nose 110 at the bottom of the frog projecting forward of said edge, of a share having a shin which extends to the top of the frog and a wing which conforms to and rests upon the wing of the frog, the share also having a rear- 115 wardly facing abutment which is engaged by the forward edge of the frog, lugs at the top and bottom of said abutment, said lugs respectively engaging the top and bottom of the frog, the bottom lug being spaced 120 from the wing of the share to admit the nose of the frog between said lug and wing, the share also having its wing formed with a lug which engages the wing of the frog.

13. In a plow, the combination with a 125 frog having a wing and a landside side, a landside secured thereto and having its front end alined with that part of the frog thereabove to constitute therewith a forwardly facing edge extending approxi- 130

- mately from the top to the bottom of the frog, the bottom of the frog and the front end of the landside having alined, undercut, forwardly open recesses and the frog having 5 a nose projecting forwardly of said recesses, a share having a shin which extends to the top of the frog and a wing which conforms to and rests upon the wing of the frog, the share also having a rearwardly facing abut- 10 ment which is engaged by the before-mentioned forward edge, lugs at the top and bottom of the abutment, said lugs respectively engaging the top of the frog and in the recesses of the frog and landside, the 15 bottom lug being spaced from the wing of the share to admit the nose of the frog between the lug and wing and said wing of the share having a lug which engages the wing of the frog.
- 20 14. A frog for plows having a landside side that is longitudinally recessed along its lower portion to provide an overhanging flange intermediate its height, and also having the forward end of its recessed portion 25 formed with a forwardly open recess and a nose which projects in advance of the forwardly open recess.
15. A frog for plows, having a landside side that is longitudinally recessed along its 30 lower portion to provide an overhanging flange intermediate its height and also having a forwardly open, undercut recess in the lower portion of its recessed part, a nose which projects in advance of the forwardly 35 open recess and a wing having a notch in its lower edge.
16. A share for plows comprising a soil turning wing a landside face and a shin, the 40 said shin being complementally formed by upward extensions of the landside face and the soil turning wing, the rear edge of the landside face and of that part of the shin which constitutes an extension thereof lying substantially at right angles to the landside 45 face to constitute a rearwardly facing abutment and that part of the shin formed by the extension of the soil turning wing projecting rearwardly beyond said abutment

and lugs projecting rearwardly from the top and bottom of the abutment.

17. A share for plows comprising a soil turning wing, a flat landside face, a rearwardly projecting lug at the bottom of said landside face spaced from the wing to provide a cavity therebetween and a rearwardly 55 facing abutment lying substantially at right angles to the landside face.

18. A share for plows comprising a soil turning wing, a landside face and a shin, the 60 said shin being complementally formed by upward extensions of the landside face and the soil turning wing, the rear edge of the landside face and of that part of the shin which constitutes an extension thereof lying substantially at right angles to the landside 65 face to constitute a rearwardly facing abutment, and lugs projecting rearwardly from the top and bottom of the abutment, said lower lug being spaced from the soil turning 70 wing to provide a cavity therebetween and being greater in width than the width of the abutment.

19. A share for plows comprising a soil turning wing, a landside face and a shin, the 75 said shin being complementally formed by upward extensions of the landside face and the soil turning wing, the rear edge of the landside face and of that part of the shin which constitutes an extension thereof lying substantially at right angles to the 80 landside face to constitute a rearwardly facing abutment, lugs projecting rearwardly from the top and bottom of the abutment the lower of the said lugs being spaced from the soil turning wing to provide a cavity 85 therebetween and a rearwardly projecting lug upon the rear edge of the soil turning wing adapted to engage beneath a part of the frog of a plow.

In testimony whereof I have hereunto set 90 my hand in presence of two subscribing witnesses.

CHARLES T. RAY.
